APPARATUS FOR ARRANGING ARTICLES
ON CONVEYERS

James M. Paton, Fort Williams, Ontario, Canada

Application July 28, 1948, Serial No. 41,136
In Canada June 8, 1948

3 Claims. (Cl. 198—29)

1

The invention relates to conveyors of the endless-carrier type for carrying crosswise of the carrier elongated, approximately straight articles such as logs or lumber, and is concerned with apparatus for automatically arranging the articles in uniform crosswise position on the conveyor.

Conveyors for elongated articles usually consist of parallel spaced apart endless chains each having a row of upward projecting members, called dogs, for engaging the articles and propelling them sideways along the conveyor. Each projecting member in one chain is aligned transversely of the conveyor with a projecting member in the other chain, and each article is intended to lie at right angles to the direction of conveyance in front of a pair of transversely aligned projecting members. When an article is conveyed by transversely aligned projecting members, it is discharged in an orderly manner suitable for piling or feeding to a machine such as a saw. However, it often happens that an article becomes improperly located on the conveyor in front of one projecting member of one pair and the projecting member of the next leading pair on the opposite side of the endless carrier and, when discharged, the article is not in a proper position for piling or feeding to a machine.

According to the invention, apparatus is provided for automatically correcting the position of an article which is improperly located on the conveyor in the manner described by clearing the article from the leading projecting member so that the article will be engaged by a pair of transversely aligned projecting members. This apparatus comprises a pair of transversely aligned levers mounted one beside each of the rows of projecting members, resilient means normally holding the levers in upright position in the path of the articles propelled by the projecting members but adapted to allow the levers to pivot to positions below the projecting members when under the weight of an article, means in connection with each lever adapted to lock the other lever after a given pivotal movement in the direction of travel of the conveyor in a position in which the other lever constitutes a skidway for clearing the article from a projecting member of the row beside said other lever, and means for releasing the locking means acting on one lever when the other lever is pivoted through said given degree.

The invention will be further described by reference to the attached drawings which illustrate an embodiment of it, and in which:

Figure 1 is a perspective view of a section of

2

a horizontal type log conveyor fitted with apparatus according to the invention,

Figure 2 is a plan view showing the interlocking rods used in the apparatus according to the invention,

Figure 3 is a side view of the conveyor shown in Figure 1, and

Figure 4 is a sectional view taken on the line 4—4 of Figure 3.

In the drawings, the conveyor shown is a horizontal type, double chain, log conveyor with log propelling dogs 10 inserted in each chain 11 and 12. The chains 11 and 12 are endless and driven along tracks 13 and 14 which are supported by a conveyor framework 15. As shown in Figure 1, each dog 10 in chain 11 moves in transverse alignment with a dog 10 in chain 12. A log 16 is shown being carried by the chains 11 and 12 in front of one dog 10 of one transversely aligned pair and a dog 10 of the next leading pair of transversely aligned dogs 10, and another log 17 is shown being properly conveyed with its ends in front of a pair of transversely aligned dogs 10.

Levers 18 and 19 are pivotally mounted at points 20 and 21 respectively so that they may pivot from an upright position to a position below the chains 11 and 12. Levers 18 and 19 have slots 22 and 23 which are circular in shape with centres at the points 20 and 21 respectively. Links

24, which are pivotally connected to each lever below the points 20 and 21, connect to interlocking rods 26 and 27 through bell cranks 25. The rod 26 operated by the lever 18 passes through a bushing 28 in the frame member 15 to engage the lever 19 in its slot 23 and, in a similar manner, the rod 27 operated by a lever 19 passes through a bushing 29 to engage the slot 22 in the lever 18. A spring 30 connects each lever 18 and 19 to the frame members 15 urging them into upright position.

In operation, a log carried in front of a pair of transversely aligned dogs (for example log 17), almost simultaneously strikes the levers 18 and 19 pivoting them forward and causing the bell cranks

25 to withdraw the interlocking rods 26 and 27 from engagement in the slots 22 and 23. Both levers are then free to pivot forward to a position below the chains 11 and 12, and the log 17 is free to be propelled forward in the direction of conveyance. However, when a log becomes located on the conveyor in the slanting position of the log 16, shown in Figures 1 and 3, its forward end engages only the lever 19 causing it to pivot forward and withdraw the interlocking rod 27 from the slot 22 in the lever 18. Since the lever

18 remains in upright position the interlocking rod 26 is not withdrawn from the lever 19 and it may only pivot an amount determined by the length of the slot 23. The amount of pivoting of the lever 19 is only that sufficient to provide a skidway for the end of the log 16 to be raised over the top of the dog 18 which is propelling the end against the lever 19. (See Figure 3.) When the end of the log 16 is free of the dog 18 it slides down the skidway formed by the lever 19, coming to rest on the chain 12 in front of a dog 10 which is in transverse alignment with the dog propelling the other end of the log 16. The log 16 is then carried forward crosswise of the conveyor and strikes both levers substantially at the same time causing them to act in the manner described in connection with log 17.

What I claim as my invention is:

1. For use with a conveyor of the horizontal endless-carrier type having members projecting from the endless carrier in two spaced-apart longitudinal rows with the projecting members aligned transversely in pairs adapted to engage and propel an elongated approximately straight article along the conveyor while extending transversely thereof, apparatus for automatically correcting the position of an article which is positioned on the conveyor in front of one projecting member of one pair and the projecting member of the next pair on the opposite side of the endless carrier by clearing the article from the projecting member of the leading pair to bring the article in front of both projecting members of the other pair comprising, a pair of trans-

versely aligned levers pivotally mounted one beside each of said rows of projecting members, resilient means normally holding said levers in upright position in the path of articles propelled by the projecting members but adapted to allow said levers to pivot to positions below the projecting members when under the weight of an article, means in connection with each lever adapted to lock the other lever after a given pivotal movement in the direction of travel of the conveyor in a position in which said other lever constitutes a skidway for clearing the article from a projecting member of the row beside said other lever, and means for releasing the locking means acting on one lever when the other lever is pivoted through said given degree.

2. Apparatus as defined in claim 1 in which the means in connection with each lever adapted to lock the other lever includes a pair of rods each operated by one of said levers, each of said levers having a slot below its pivotal axis in which an end of the rod operated by the other of said levers is adapted to be inserted to limit the pivoting of that lever to that necessary to provide the skidway for clearing the article from a projecting member of the row beside that lever when said other lever is in its upright position.

3. Apparatus as defined in claim 1 in which the conveyor is of the double chain type for conveying logs, and the projecting members are log-propelling dogs inserted in each chain.
